DESIGN FOR A HANDBAG OR SIMILAR ARTICLE

Florence Kuhlman, New York, N. Y., assignor to Robert Appel, New York, N. Y.

Application May 21, 1940, Serial No. 92,494

Term of patent 3½ years

To all whom it may concern:

Be it known that I, Florence Kuhlman, a citizen of the United States, residing at New York city, in the county and State of New York, have invented a new, original and ornamental, Design for a Handbag or Similar Article, of which the following is a specification; reference being had to the accompanying drawing, forming part thereof.

Fig. 1 is a perspective view of a handbag or similar article, showing my new design.

Fig. 2 is a side view of one of the plaque elements of the design.

The side and end of the handbag not shown in Fig. 1 of the drawing are substantially like the side and end shown.

The characteristic features of the design reside in the ornamentation of the handbag.

I claim:

The ornamental design for a handbag or similar article, substantially as shown and described.

FLORENCE KUHLMAN.
